ELECTRIC VARIABLE CONDENSER

Peter Grassmann, Berlin, Germany

Application October 24, 1933, Serial No. 695,023
In Germany August 10, 1932

5 Claims. (CL 175—41.5)

This invention relates to electric variable condensers and more particularly to condensers of the type which are commonly employed in radio apparatus, usually for tuning purposes.

5 An object of this invention is to provide a variable tuning condenser which will be of maximum electrical capacity while occupying a minimum amount of space. Another object is to provide a variable condenser embodying improved 10 means for accurately and uniformly spacing the vanes thereof.

These and other objects which will be more apparent hereinafter are attained in accordance with this invention by making both the fixed and 15 movable condenser vanes of extreme thinness, so thin as to be non-rigid and incapable of supporting their own weight, and mounting the vanes of each set in a rigid frame in which the vanes are tensioned so as to lie in parallel planes. By 20 this means it is possible to reduce the spacing between the vanes to a minimum and this, together with the extreme thinness of the vanes, makes practicable a large capacity condenser of minimum dimensions. Compact condensers of 25 midget proportions, which are extremely accurate in spite of their smallness, can thus be constructed, and this assists towards reducing the size and bulkiness of radio sets.

For a clearer understanding of the invention, 30 one specific embodiment thereof will be described in the following, reference being had to the accompanying drawing, in which

Fig. 1 illustrates a section on the line A—B of Figure 2, which illustrates in plan view a preferred form of condenser embodying the invention. The position of the set of moving plates in the position of minimum capacity is shown in 35 chain-dotted lines.

Referring to the drawing, the spacings between 40 the vanes 1 and the thicknesses of the latter as represented in Fig. 1 are merely diagrammatic and are not intended to show the actual dimensions employed. Also, while Fig. 1, being a section on line A—B of Fig. 2, illustrates the set of 45 fixed vanes, the set of moving vanes may be similarly represented.

The vanes 1 consist of extremely thin metal 50 wafers or foils, for instance, 0.05 mm. in thickness, and preferably of hard metal, for instance, copper or brass. The vanes are spaced by metallic 55 spacing washers 2 of, for instance, 0.5 mm. thickness. In the drawing, a set of twelve vanes is illustrated as an example. With the dimensions given, the overall depth of the entire set 55 is practically only 6.1 mm.

The fixed and moving set of vanes are mounted in tensioning frames 4 and 7, respectively. These frames are similarly constructed and therefore a detailed description will be given only in connection with the frame 4 for the fixed vanes, it being understood that frame 7 is similar except in respect of such details as will hereinafter be specifically mentioned.

The frame 4 corresponds in outline to the final shape or configuration of the vanes 1 which in 10 the construction illustrated are in the form of right-angle triangles, the sides of which are of unequal length. I have found by experiment that this is one of the most suitable shapes. Also, in the construction illustrated in Fig. 2, the frame 15 4 is constructed as a double frame. The upper and lower members of the frame 4 are connected together by the rods 3 located at the angles of the triangular members. The rods 3 are hollow in order to facilitate the fixture of the set of 20 fixed vanes to a casing and at the same time to facilitate the connection of a number of condensers in series. Of course, the fixing of the condenser in the casing may be effected in a different manner; for instance, by means of lugs 25 or feet provided on the frame 4.

Each condenser vane is stamped with its holes, for mounting on the rods 3, under simultaneous plane-pressure, the holes being shaped such that after the vane and spacing washers 2 have been 30 mounted in position on the rods 3 of the frame 4, tensioning or stretching of the vane so as to make it assume a plane surface is still possible. In practice, it is sufficient for this purpose to make the holes in the vanes somewhat larger 35 than the diameter of the rods 3, so that the vanes can be loosely mounted on the latter.

In the case of the fixed vane assembly, spacing bushes 6 (see Fig. 1) are provided between the end vanes 1 and the triangular members of the 40 frame 4 in order to provide the necessary clearance space for the passage of the triangular members of the frame 7 carrying the moving vanes. The moving vane assembly on the frame 7 will, of course, not include bushes similar to 45 the bushes 6 of the fixed frame assembly.

The fixed and moving vanes and also their frames form, as can be seen from the drawing, equal triangles, which substantially simplifies manufacture. Each frame has a bracket 8 which 50 extends along its shortest edge and which, together with the hollow spindle 9, forms the bearing for the moving frame 7 and vanes. In this case, the frame 4 is insulated from the frame 7 and the spindle 9 by insulating bushes 10. The 55

spindle 9 is firmly connected, in a manner not shown in detail, to the brackets 8 of the frame 7 and may be combined with either an operating knob or transmission gear, or with the spindle of 5 an adjacent condenser, for ganging purposes. It will be noted that the spindle 9 is located at a point outside the effective surface of the moving vanes.

In the drawing, the rotating knob drive for the 10 condenser which is fixed by means of screws to a base plate, is illustrated.

In Fig. 2, the position of the set of moving vanes at minimum capacity is represented by the 15 chain-dotted lines. It will be seen that movement of the moving vanes completely from between the fixed vanes is prevented by the presence of the frames, so that a certain small "initial" or "residual" capacity arising from the overlapping cannot be avoided. In order to reduce 20 this "initial" capacity, according to a feature of this invention, both the fixed and movable vanes are provided with recesses 11 at the angles which overlap and produce the "initial" capacity, positioned and proportioned such that, in the position 25 of minimum capacity, these recesses cross one another and thus only punctiform parts of the plates are opposite one another.

While it is preferable to use metallic frames, I do not wish to exclude the use of frames of 30 insulating material. In the latter case, the insulating bushes 10 become unnecessary.

The tensioning of the foils may be done in any suitable manner; for instance by means of a tool 35 in which the lugs of the vanes are clamped. The tool may either be a tong-like clamping device provided with spacing members corresponding to the spacing members 2, or it may be a threaded bolt provided with similar spacing members between which the vanes are clamped and then 40 tensioned all at the same time, that is to say, first at one corner of the triangle and then at the second and third corner. When one side of the triangle has been straightened out, the nuts 5 are tightened and the procedure is repeated at 45 the second and third corners. Naturally, the first corner (preferably the one having the 90° angle) may be clamped at once, for which reason the tensioning has to be done only from the two acute-angled corners.

50 I claim:—

1. An electric variable condenser comprising two rigid frames so mounted as to permit one to rotate within the other, and condenser vanes mounted in each of said frames, said vanes being so thin as to be non-rigid and incapable of supporting their own weight and being in stretched condition so as to lie in parallel planes within said frames. 5

2. An electric variable condenser comprising two rigid frames so mounted as to permit one to rotate 10 within the other, and condenser vanes mounted in each of said frames, said frames and vanes being so shaped and proportioned that in the position of minimum capacity small areas of said fixed and said movable vanes overlap, and means 15 for reducing the minimum capacity due to said overlapping surfaces, said vanes being so thin as to be non-rigid and incapable of supporting their own weight and being in stretched condition so as to lie in parallel planes within said frames. 20

3. An electric variable condenser comprising two rigid frames so mounted as to permit one to rotate within the other, and condenser vanes mounted in each of said frames, said frames and vanes being so shaped and proportioned that in the 25 position of minimum capacity small areas of said fixed and said movable vanes overlap, and slots in said vanes at said overlapping areas, so positioned and shaped as to lie across one another and thereby reduce the minimum capacity due to 30 said overlapping surfaces, said vanes being so thin as to be non-rigid and incapable of supporting their own weight and being in stretched condition so as to lie in parallel planes within said frames. 35

4. In the manufacture of an electric variable condenser, the steps of mounting a non-rigid wafer-like condenser vane on a rigid frame forming part of the condenser assembly, stretching said vane until it assumes the form of a plane 40 surface, and clamping said vane in such stretched condition.

5. An electric variable condenser according to claim 1, characterized in that the said frames are of right-angle triangular form, one of which is 45 rotatable with respect to the other about an axis lying adjacent but spaced from the right angle of the frame and outside the effective surfaces of the said condenser vanes.

PETER GRASSMANN.
